Primary Examiner — Joseph Kukella*Assistant Examiner* — Arva P Adams(74) *Attorney, Agent, or Firm* — Westbridge IP LLC(57) **CLAIM**

The ornamental design for a barbecue grill ring shelf, as shown and described.

DESCRIPTION

FIG. 1 is a front perspective view of a barbecue grill ring shelf showing my new design;

FIG. 2 is a rear perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a partial enlarged view taken from circle 9 in FIG. 1; and,

FIG. 10 is a partial enlarged view taken from circle 10 in FIG. 1.

The dash-dash broken lines in the drawings illustrate the portions of the barbecue grill ring shelf which form no part of the claimed design.

The dot-dash broken lines in the drawings are included for the purpose of illustrating the partial enlarged views.

1 Claim, 10 Drawing Sheets(56)
